United States Patent

Des. 237,880

Patented Dec. 2, 1975

237,880

BASIC HAND TOOL EDUCATIONAL BOARD

Charles G. Valentine, Stamford, Conn., assignor to
Xerox Corporation, Stamford, Conn.

Filed Apr. 19, 1973, Ser. No. 352,797

Term of patent 14 years

Int. Cl. D19—07

U.S. Cl. D19—62

FIG. 1

FIG. 2

FIG. 1 is a left perspective view of a basic hand tool educational board showing my new design; and

FIG. 2 is a right perspective view thereof.

The rear of the basic hand tool educational board not shown is plain and unornamented.

I claim:

The ornamental design of a basic hand tool educational board, substantially as shown and described.
